UNITED STATES PATENT OFFICE.

FRANK M. FABER, OF PITTSBURG, PENNSYLVANIA, ASSIGNOR TO THE PITTSBURG PNEUMATIC COMPANY, OF CANTON, OHIO, A CORPORATION OF NEW JERSEY.

FLUID-PRESSURE TOOL.

No. 853,201.

Specification of Letters Patent.

Patented May 7, 1907.

Application filed July 29, 1905. Serial No. 271,863.

To all whom it may concern:

Be it known that I, FRANK M. FABER, a resident of Pittsburg, in the county of Allegheny and State of Pennsylvania, have invented a new and useful Improvement in Fluid-Pressure Tools; and I do hereby declare the following to be a full, clear, and exact description thereof.

My invention relates to pneumatic tools for calking boilers and tanks, forming rivet heads, carving stone, etc.

One of the objects of my invention is to provide a device of this character in which the full pressure of the air follows the piston throughout its entire stroke toward the tool, while at the same time to obtain a minimum recoil by causing the piston to come to rest gradually by using the fluid which produces the stroke away from the tool expansively so that the pressure on the piston at the instant that it reverses its motion is practically *nil*, and lastly by causing the compressed air to cushion on itself, so to speak, at the instant of its entrance to the cylinder.

To these ends my invention comprises, generally stated, a suitable body portion having a cylindrical chamber therein, a piston in said chamber, a valve chamber and a valve therein controlling ports leading to said cylindrical chamber and to a reservoir into which air is admitted simultaneously with its entrance to the cylinder, whereby the air in said reservoir will act as a cushion to prevent the too sudden application of pressure to the piston, and the drop in pressure at the induction port is almost entirely compensated for by energy given out by fluid stored in said reservoir.

My invention further comprises certain other new and novel features, all of which will be fully hereinafter set forth and claimed.

Referring to the accompanying drawings Figure 1 is a longitudinal view of my improved tool; Fig. 2 is a cross sectional view; Figs. 3 and 4 are diagrammatic views which illustrate more readily the arrangement of ports and which respectively show the valve in positions for directing the fluid pressure to produce the forward and return strokes of the piston; and Fig. 5 is a sectional view of a modified form of part of my valve mechanism.

In the drawings the numeral 2 designates a suitable body which may be of any suitable

form, and which is provided with the cylinder 3. Within the cylinder 3 is a piston 4 fitting snugly within said cylinder. At the rear end of the body 2 is the valve shell or casing 5 to which is secured or formed integral therewith the handle 6 for convenience in manipulating the tool. Within the valve casing 5 is the valve chamber 7 which contains a piston valve 8, although I do not wish to be understood as limiting myself in any way to such a piston valve, or in fact any particular form of valve. This valve 8 is provided with the rings or collars 9 10 11 12 and 13, and said valve is adapted to move freely back and forth within the said chamber 7. Within the body of the valve 8 is the chamber 14 within which fits the plunger or movable member 15, said plunger being preferably free from the head 16 of the valve casing 5.

Orifices 17 put the valve chamber 7 in communication with the chamber 14 and the main supply port 18 supplies the air to the said chamber 7. The pressure of the air in the chamber 14 normally acts to hold the valve in the position indicated in the diagrammatic view Fig. 3, or at the right end of the valve chamber.

A port 19 leads from the valve chamber 7 to the cylinder 3 and a port 20 leads from said valve chamber to the reservoir 21. This reservoir 21 may be conveniently located in the handle 6, although I do not wish to limit myself in any way to this location, as it may be located in the body of the tool if desired. The handle 6 is provided with the plug 22 which closes the reservoir 21 and this plug may be screwed up within the reservoir so as to reduce the size of said reservoir if desired.

The port 23 leads from the valve chamber 7 and enters the cylinder 3 at the point 23^a, which is at a distance somewhat greater than the length of the piston 4 from the rear end of the cylinder 3. A branch port 23^b may also connect the cylinder 3 with the port 23. The port 24 leads from the valve chamber 7 to the front end of cylinder 3 and the port 25 leads from the valve chamber 7 to a point in the cylinder 3 at a distance from its front end greater than the length of the piston 4. An exhaust port 26 leads from the valve chamber 7 to the atmosphere. A second exhaust port 27 also leads from the valve chamber 7 to the atmosphere. A port 28 leads from the

valve chamber 7 to the space 29 at the right end of the valve 8 back of the collar 13.

For convenience in operating a throttle valve of any suitable construction should be located in the port 18 so as to control the supply of air to the valve chamber 7.

The operation of my improved tool is as follows, and by reference to the diagrammatic views represented in Figs. 3 and 4 its

- 10 operation will be more readily understood: When the valve 8 and piston 4 are in position shown in Fig. 3, fluid pressure admitted through the port 18 enters the chamber 14 through the orifices 17 and holds the plunger 15 firmly against the head 16, and forces the valve to the limit of its stroke toward the right, as clearly shown. As the orifices 17 are always in communication with the feed supply pressure admitted to the chamber 14
- 20 the valve is held in the position shown in Fig. 3 until a superior force is introduced to drive the valve toward the left or into the position shown in Fig. 4. Fluid pressure also simultaneously enters the cylinder 3 and the reservoir 21 through ports 19 and 20 respectively, the piston 4 now starting on its forward stroke. By permitting the fluid pressure to enter the reservoir and cylinder in this manner I gain a two-fold result: first,
- 30 the recoil is greatly modified, since the fluid entering the reservoir will act as a cushion to prevent the too sudden application of pressure to the piston; and second, the drop in pressure at the induction port 18 which would otherwise be marked as the piston reached the completion of its forward stroke, is almost entirely compensated for by energy given out by fluid stored in the reservoir. The piston advances then under practically initial
- 40 pressure until it strikes the tool 30. As the piston 4 advances the fluid in front thereof exhausts through the ports 24 and 27. Just before reaching the end of its forward stroke the piston passes the port 25 and admits fluid pressure against the opposing annular surfaces of the rings or collars 12 and 13. The area of the annular surface of the collar 12 being larger than that of 13 the introduction of fluid pressure between them tends to throw
- 50 the valve toward the left and by making the areas of these rings or collars such that the difference in their areas is greater than the cross area of the plunger 15, the tendency exerted by fluid pressure in the chamber 14 is overcome and the valve is thrown to the left.
- 60 The result of moving the valve toward the left is as follows: first, the collar 10 closes communication between the induction port 18 and the reservoir 21 and at or about the same instant the collar 11 closes the port 19; second, the collar 9 passes beyond the port 28 and admits pressure from the reservoir 21 to the space 29 and against the end of the valve or the collar 13, thus acting to complete its throw; and third, the collar 11 passes and

opens port 23, allowing fluid pressure in the cylinder 3 to exhaust through ports 23 and 26. At or about the same instant the collar 9 passes the port 24, when the parts will all have assumed the positions shown in Fig. 4. Fluid pressure in the reservoir 21 now passes through the port 20 into the annular space between the collars 9 and 10, thence through the port 24 to the front end of the cylinder.

By admitting pressure from the reservoir to the space 29 a complete throw of the valve under all conditions is insured. Should the port 28 be omitted and the movement of the valve toward the left be entirely dependent on pressure admitted through the port 25 the hammer would not start when standing vertically, the forward end down. When in this position the piston drops to the front end of the cylinder, as shown in Fig. 4. If now the throttle should be opened the valve would be thrown to the right by pressure in the cylinder or chamber 14, as before, when pressure would pass through the cylinder and into the space 7 by port 25 starting the valve toward the left. The moment, however, the port 23 is opened pressure in the cylinder and space 7 exhausts into the atmosphere through the exhaust 26 and the valve is thrown to the right by pressure in 14 as already explained. So then under the conditions just described, the valve would not make its complete stroke but would stop entirely or "flutter" at the point of its throw when exhaust begins. Accordingly I so proportion the parts that the port 28 opens and admits pressure from the reservoir to the space 29 before the exhaust begins, and as I make the diameter of the ring 13 greater than the diameter of the chamber 14, the valve will be thrown completely over under all conditions and be held rigidly in place until the normal reverse movement is required. The piston having completed its forward stroke, and the valve being in the position shown in Fig. 4, the action of my hammer continues as follows: Fluid pressure enters the front end of cylinder 3 and acting expansively starts the piston on its backward or return stroke. When the piston passes port 23^a compression begins and gradually brings the piston to rest. When the piston passes entirely beyond 23^a the fluid pressure in the reservoir, the front end of the chamber 3, the space 7^a and the end 29 of the valve chamber, exhausts through ports 23^a, 23 and 26. The fluid pressure in spaces 7^a and 29 being now reduced to that of the atmosphere, the fluid pressure in cylinder 14 at once throws the valve into the position shown in Fig. 3, when the cycle of operations just described is rapidly repeated.

It is evident that by properly proportioning the volume of the reservoir to volume of cylinder the fluid pressure used for producing the return stroke of the piston may be expanded down to any pressure desired at the

point of exhaust. As described above the valve is held in the position shown in Fig. 4 by fluid pressure admitted from the reservoir through the passage-way 28 to the space in 5 the valve chamber 29. It is evident that by suitably decreasing the volume of the reservoir the fluid pressure therein may during the 10 return stroke be expanded down to a pressure desired before the piston 4 passes and opens the exhaust port 23^a; consequently the relative volumes in the reservoir and cylinder may be so proportioned that the pressure in the reservoir may be expanded to a point where the pressure in the chamber 29 will not 15 be sufficient to hold the valve in the position shown in Fig. 4 against the constant pressure in the chamber 14. Under these conditions the valve will be thrown into the position shown in Fig. 3 and air admitted 20 through port 19 to produce the forward stroke before the piston 4, while on its return stroke, passes the exhaust port 23^a, and consequently the length of stroke may be reduced to any desired extent by a suitable 25 reduction of volume of reservoir.

In Fig. 5 I have shown a modified arrangement of the plunger and chamber to receive the fluid pressure and hold the valve in the position shown in Fig. 3. In this case the 30 chamber 40 is formed in the end or head of the valve chamber and the fluid pressure confined therein exerts a continuous tendency to move the valve in a given direction or toward the right, as shown in the accompanying 35 drawings.

It is obvious that other methods than those described may be employed for actuating the valve without departing from the spirit of my invention, and that valves of different types 40 may be employed instead of the one illustrated. Furthermore, it is obvious that the location of the reservoir may be changed and that various other changes may be made in the form, proportions and location of parts 45 and still come within the scope of my invention.

What I claim is:

1. In a fluid pressure operated tool, a suitable body portion having a cylinder, a piston, a valve controlling the ports to said cylinder, and a reservoir communicating with said cylinder, and means for operating said valve to alternately connect said reservoir with the fluid pressure supply and with said cylinder.
2. In a fluid pressure tool, a suitable body portion having a cylinder, a piston, means for reciprocating said piston, a reservoir communicating with said cylinder, and means for varying the volume of said reservoir.
3. In a fluid pressure tool, a suitable body portion having a cylinder, a piston, a reservoir, a valve controlling ports leading to said cylinder and reservoir, and means for ad-

mitting fluid pressure simultaneously to said cylinder and reservoir.

4. In a fluid pressure tool, a suitable body portion having a cylinder, a piston, a reservoir, a valve controlling ports leading to said cylinder and reservoir, and means for moving said valve by fluid pressure from said cylinder and said reservoir.

5. In a fluid pressure tool, a suitable body portion having a cylinder, a piston, a reservoir, a valve controlling ports leading to said cylinder and reservoir, and means for moving said valve by fluid pressure from said reservoir.

6. In a fluid pressure tool, a suitable body portion having a cylinder, a piston, a reservoir, a valve controlling ports leading to said cylinder and reservoir, and a port communicating with said reservoir and carrying fluid pressure to the valve chamber to operate said valve.

7. In a fluid pressure tool, a suitable body portion having a cylinder, a piston, a reservoir, a valve controlling ports leading to said cylinder and reservoir, means for carrying fluid pressure from the forward end of said cylinder to the valve chamber and from said reservoir to move said valve.

8. In a fluid pressure tool, a suitable body portion having a cylinder, a piston, means for reciprocating said piston, a handle, and a reservoir in said handle communicating with said cylinder.

9. In a fluid pressure tool, a suitable body portion having a cylinder, a piston, a valve controlling the movement of said piston, said valve having a chamber therein communicating with the fluid pressure supply, a plunger in said last named chamber, collars of different areas at one end of said valve, means for admitting fluid pressure to the space between said collars, the difference in areas of said collars being greater than the area of said chamber, whereby said valve is moved against the pressure within said chamber.

10. In a fluid pressure tool, a suitable body portion having a cylinder, a piston therein, a valve controlling ports leading to opposite ends of said piston, and a port conducting fluid from said cylinder to the valve chamber and thence to the atmosphere and beyond which the entire piston passes when moving in both directions.

11. In a fluid pressure tool, a suitable body portion having a cylinder, a reciprocating piston therein, a valve chamber, a valve within said chamber controlling the motion of said piston and a main exhaust passage controlled by said valve, a main exhaust port connecting the passage with the cylinder at a distance from its rear end and beyond which the entire piston passes when moving in both directions, and a branch port to said passage between the rear end of the cylinder and said main exhaust port.

12. In a fluid pressure tool, a suitable body portion having a cylinder, a piston, a reservoir, a valve for controlling ports leading to said cylinder and reservoir, and means for holding said valve in one position by pressure from said reservoir.

13. In a pneumatic pressure tool, a suitable body having a cylinder, a reciprocating piston within the cylinder, a reservoir supplying fluid pressure to the cylinder to force the piston in one direction, and means for in-

creasing or diminishing the volume of the reservoir to produce a corresponding increase or reduction in length of stroke of the piston.

In testimony whereof, I the said FRANK M. FABER have hereunto set my hand,

FRANK M. FABER.
